(57) **CLAIM**

The ornamental design for a detachable segmented carrying bag, as shown and described.

DESCRIPTION

FIG. 1 is a front elevational view showing a detachable segmented carrying bag which forms my new design;

FIG. 2 is a left side elevational view thereof showing the zippered face-to-face attachment of the pair of carrying bag segments;

FIG. 3 is a rear elevational view thereof;

FIG. 4 is a right side elevational view thereof also showing the zippered face-to-face attachment of the pair of carrying bag segments;

FIG. 5 is a top plan view thereof;

FIG. 6 is a bottom plan view thereof;

FIG. 7 is a front elevational view showing the front face of one of the pair of carrying bag segments unzipped and detached from the second of the pair of carrying bag segments;

FIG. 8 is a rear elevational view showing the rear face of the second of the pair of carrying bag segments unzipped and detached from the first of the pair of carrying bag segments;

FIG. 9 is an exploded view thereof showing the tops of the pair of carrying bag segments unzipped and detached from one another; and,

FIG. 10 is an exploded perspective view thereof showing the tops, left sides and fronts of the pair of carrying bag segments unzipped and detached from one another.
